A. G. GREENWOOD,
HANDY BOOK AND TRAY STAND,
APPLICATION FILED APR. 3, 1920.

1,396,700.

Patented Nov. 8, 1921.

WITNESS:

Mrs. Annie Lawrence
G. T. Pollard

INVENTOR

A. G. Greenwood

UNITED STATES PATENT OFFICE.

ANNA G. GREENWOOD, OF DENVER, COLORADO.

HANDY BOOK AND TRAY STAND.

1,396,700.

Specification of Letters Patent.

Patented Nov. 8, 1921.

Application filed April 3, 1920. Serial No. 371,083.

To all whom it may concern:

Be it known that I, ANNA C. GREENWOOD, a citizen of the United States, residing at Denver, State of Colorado, have invented certain new and useful Improvements in Handy Book and Tray Stands, of which the following is the specification.

The first object of the invention is to provide a means for conveniently holding a book, which because of its design may easily be changed from a book stand into a tray, stand or table.

A further object of the invention is to provide means for the proper adjustment of its parts, so that the same parts may be conveniently arranged to hold a book for a person while lying down or may be readily changed to another convenient position.

A further object of the invention is to provide means for holding a tray in any convenient position, for a person sitting up in bed, or the same parts may be changed and suitably arranged to hold a copy for a person while their hands are engaged in some other manner.

In the accompanying drawings, Figure 1 and Fig. 2, show the front and side elevations of the handy stand arranged for holding a book. Fig. 3, shows a detailed section of the swiveled head, and Fig. 4, shows a side elevation which shows the arrangement of parts when the stand is used to hold a tray. Fig. 5 shows the detail of the ball and socket nut, shown by drawing 35 on Sheet #2.

In the description the parts are indicated by numerals. The base (1), has a weighted foot with a tubular upright body at the upper end of which is a screw head (2), from which the upper neck (5) projects. This upper neck may be turned, raised or lowered and when properly adjusted, it may be fastened in position by a hand screw. On the side of the main base is hinged side table (3), which may be raised as shown in Fig. 2, or lowered to position shown in Fig. 4. The upper neck (5) projects upward and outward from the main base (1). At the outer end of this neck (5) is fastened a fixed T-head (8). In this T, a swiveled head bolt (12) turns to any desired position about a vertical axis. From the upper end of the swivel head rises a lamp neck (6), which projects outward to a proper position for an electric lamp (7). The lamp may be turned to any desired

position, about a vertical axis. Just below the fixed T-head (8) and around the swivel head bolt (12) is a spring washer (9), which allows a slight compression between the parts to hold them in a positive position without undue stress. Just below the spring washer (9), and turning on the swivel head T (12) is the swivel head T (10), in the side of which is a threaded stud on which may be screwed a hand nut (11^a), which when turned secures the ball and socket nut (13), which is attached to the book stand (14). This position is shown in Fig. 2. The lower end of the swivel bolt (12) is threaded also, on which turns the hand nut (11), which when turned up holds the swivel head and lamp bracket into any desired position. Below the nut (11) is sufficient room on the threaded part of swivel bolt (12), to screw on the ball and socket nut (13), which is attached to the stand (14), when the stand is used as a tray stand or table as shown in Fig. 4. In this position, the spring clamps (15) hang downward and rest on the bed or on any other support. This makes an additional support for the table. In Fig. 2, when the stand (14) is used to hold a book, the spring clamps (15) are slid along the rod (16). This rod is secured to the lower part of the stand (14). The upper part of the two spring clamps (15) are notched so as to properly fit over the upper edge of the stand and properly hold the springs in such a position to hold the different thicknesses of the books. The electric wires (17) are passed up from the base through the tubes 1, 5, 8, 12 and 6 to the electric socket (7) and these wires are properly insulated.

On Sheet #2 the drawing shows Fig. 5 a detail of the ball and socket nut (13), which is made up of three parts, a spherical nut (13^a), which may be screwed on to either the stud on swivel head T (10), or onto the lower end of swivel bolt (12). This nut is held by the socket (13^c), which is fastened to the table by bolts. A hand set screw (13^b), is inside of socket, to secure and keep the spherical nut from turning when set in desired position.

In Figs. 1 to 5 inclusive and in this description, it is clearly shown the combination and design of all the parts to form this handy book and tray stand and because of this design, the book may be conveniently held in any position; this position may be easily changed, raised or lowered or turned

about, and the same parts will serve to be used to form a tray stand or table, which may be adjusted for use on a bed or any desired rest.

5 Therefore, because of the handy usefulness of this invention, I make the following claims:

1. The combination in a set for the purpose described of a weighted foot, affixed 10 tubular upright body with hand set screw in top of tubular body, as means of holding a telescoping upper tubular neck into position, a side hinged table and bracket on upright body; an outer end fixed T-head on tubular 15 neck, as means for holding a swivel head bolt, a lamp neck and electric fixture attached to upper end of swivel bolt, as means for holding an adjustable light, a spring washer, interposed on swivel bolt to separate 20 swivel T and T-head; a swivel T with studs on side and bottom, to which may be screwed

a ball nut, which fits into joint or socket attached to table; a hand nut also on studs to fasten parts to position, parts as stated as a means of adjusting table to different 25 positions and attached to table a rod on which slides notched spring clamps, forming means for holding a book, or means for supporting table.

2. In a combination set to handily hold 30 a book or form a table, with a base, upright tubular body, a hand set screw to hold an upper tubular neck in a lower tubular upright body and a T-head attached to tubular neck, with swivel T, swivel bolt, studs, hand nuts, ball and socket joints to form an adjustable means for holding a table, with 35 sliding notched spring clamps for holding a book, on said table.

In testimony whereof, I affix my signature. 40

MRS. A. G. GREENWOOD.
